UNITED STATES PATENT OFFICE.

JOHN ROBERT SCOTT, OF FRESNO, CALIFORNIA.

DESIGN FOR A PRICE-DIAL.

46,915.

Specification for Design.

Patented Feb. 2, 1915.

Application filed July 15, 1914. Serial No. 851,186. Term of patent 14 years.

To all whom it may concern:

Be it known that I, JOHN R. SCOTT, a citizen of the United States, residing at Fresno, in the county of Fresno and State of California, have invented a new, original, and ornamental Design for a Price-Dial, of which the following is a specification, reference being had to the accompanying drawing, forming part thereof.

The figure is a front elevation of a price dial showing my new design.

I claim:

The ornamental design for a price dial, as shown.

JOHN ROBERT SCOTT.

Witnesses:

E. LA MAR-THORNBURG,
A. L. SWARTHOUT.
